Attorney.

UNITED STATES PATENT OFFICE.

GEORGE H. CARLSON, OF OMAHA, NEBRASKA, ASSIGNOR TO HOESCHEN MANUFACTURING COMPANY, OF OMAHA, NEBRASKA, A CORPORATION OF NEBRASKA.

RAILWAY-TRACK INSTRUMENT.

1,367,798.

Specification of Letters Patent.

Patented Feb. 8, 1921.

Application filed May 4, 1918. Serial No. 232,665.

To all whom it may concern:

Be it known that I, GEORGE H. CARLSON, a citizen of the United States, and a resident of Omaha, in the county of Douglas and State of Nebraska, have invented certain new and useful Improvements in Railway-Track Instruments, of which the following is a specification.

My invention relates to instruments employed in railway signaling for indicating the passage of a train over a particular portion of a railway track. It is the object of my invention to provide a simple, inexpensively constructed, durable and efficient instrument of this class, utilizing for its operation the movement of a track-rail relative to the ties or sleepers on which it is laid, but not dependent upon the maintenance of a precise range of movement of the rail, or upon definite limits to the extent of movement thereof relatively to the ties. A further object of my invention is to provide an instrument of the foregoing character adapted to be effectively operated by a comparatively minute movement of the rail. A further object of my invention is to provide an instrument of this class which may be substantially weather-proof, so as to remain operative in all seasons and under the most adverse conditions.

In the accompanying drawings Figure 1 is a longitudinal vertical section of an instrument embodying my invention the section being on line 1—1 of Fig. 2, Fig. 2 is an end view with the cover of the housing removed, Fig. 3 is a detail vertical section on the plane of the line 3—3 of Fig. 1, and Fig. 4 is a detail horizontal section on the plane of the line 4—4 of Fig. 2.

In the illustrated structure I provide a casing or housing having a main portion 5 with laterally extending lugs 6 adapted to rest upon the upper sides of two adjacent ties or sleepers A of a railway track. The open front side of the housing is normally closed by a removable plate 7 which is secured to the main body of the housing by screws 8. From the rear side of the main housing 5 an integral tubular portion 9 extends horizontally, and at its rear end has a projecting hooked lug 10 adapted to engage and rest upon a portion of a T-bar 11 extending between the ties A adjacent to a track-rail B laid upon said ties. Beneath the rail there is a vertical cylindrical por-

tion 12 formed integrally with the portion 9, the bores of said parts 9 and 12 intersecting as shown in Fig. 3. In the cylinder 12 there is slidably disposed a plunger 13, a coil spring 14 being disposed beneath said plunger and pressing the same upwardly. At the upper end of the plunger the same has an integral stem 15 which extends slidably through a packing-gland 16 formed in a screw-plug 17 employed for closing the upper end of the cylinder 12. The upper end of the stem 15 normally engages the lower side of the rail B and presses upwardly thereon, tending to hold the rail slightly above the surface of the ties A, so that when the rail is pressed down firmly upon the ties, as by the passage of a train along the track, the plunger 13 will be moved downwardly in the cylinder 12, and will be moved upwardly again by the pressure of the spring 14 when the wheel-pressure upon the rail is removed. The side of the plunger adjacent to the bore of the tubular housing-part 9 has formed thereon teeth constituting a rack 18 adapted to mesh with a pinion 19 secured on a shaft 20 which extends through the bore of the part 9. The shaft 20 is journaled in bearing-sleeves 21 and 22 disposed respectively at the front and rear ends of the tubular housing-part 9. The bearing-sleeve 21 is removable, held in place by a screw 23, and the outer portion of said sleeve is spindle-shaped, thereby enabling the same to rock within its support and assume a position of true axial alignment with the shaft. The sleeve 22 is secured in the housing by means of a key 24 of which the rear end extends into a notch in a disk 25 disposed at the end of the sleeve. A screw-plug 26 closes the end of the housing-part 9 and holds the disk 25 against a shoulder at the end of the threaded portion of the bore.

Within the main housing 5, adjoining the end of the bearing-sleeve 21, a ratchet-wheel 27 is secured to the shaft 20. Adjoining the front side of said ratchet-wheel a wheel 28 is mounted revolvably on the shaft, said wheel 28 being of greater diameter than the ratchet-wheel, and the peripheral portion or rim thereof being serrated to form a series of V-shaped teeth 29. The wheel 28 is retained on the shaft by a washer 30 and cotter-pin 31 arranged at the end of the shaft, as shown, and at the inner end 110

of the bearing-sleeve 21 there is a washer 32 and pin 33 which prevent longitudinal movement of the shaft forwardly through the bearing-sleeve. Pawls 34 pivoted on the 5 wheel 28 are pressed into engagement with the ratchet-wheel 27 by means of springs 35, whereby rotary movements of the ratchet-wheel and shaft in one direction are communicated to the notched-wheel 28. In the 10 upper part of the main housing there is pivotally mounted an arm 36 having a V-shaped end-portion 37 adapted to fit in the notches between the teeth 29 of the wheel 28. A spring 38 is arranged to press said 15 arm 36 toward the wheel, and the strength of said spring is preferably sufficient to cause movement of the wheel, by engagement of the V-portion 37 of the arm with the inclined sides of the teeth 29, should said 20 portion 37 not be seated in one of the notches between the teeth.

At the rear side of the main housing 5 there is a pin 39 on which is pivoted an arm 40 which extends approximately horizontally 25 past the periphery of the notched wheel 28 and has a forwardly extending lug 41 adapted to rest upon the upper side of one of the teeth 29, as shown in Fig. 2. At the end of the arm 40 there is a contact- 30 piece 42, which may be insulated from the body of the arm, if desired. A block 43 of insulating material is secured in the housing above the contact 42, and on said block there is carried a pair of contact-springs 35 44 which extend downwardly therefrom into proximity to the contact 42, so the latter may pass between and electrically connect them when the arm 40 is raised, as by rotation of the wheel 28 in the direction indicated in Fig. 2. Suitably insulated wires 45 are connected with the contact-springs 44 and are extended from the housing through a pipe or conduit 46 connected with one side thereof, as shown, said wires being 40 extended to and connected with any suitable electrically controlled or actuated signaling mechanism, and forming a part of the circuit through said mechanism. Near the end of the arm 40 there is a weight 47 sufficient 45 to cause the arm to move downwardly and disengage the contact 42 from the springs 44 when the arm is unsupported by the teeth 29 engaging the lug 41.

From the foregoing the operation of the 55 instrument may be clearly understood. During the passage of a train, or even of a single engine or car, along the rail B, there will be a plurality of movements of the rail relatively to the ties B, the rail being pressed 60 down onto the ties as each wheel passes over the same, and having some upward movement during the intervals between the passage thereover of the successive wheels. The movements of the rail result in vertical reciprocating movements of the plunger 13,

said plunger being pushed downwardly by the rail, and pushed upwardly by the spring 14. Said reciprocating movements of the plunger are communicated by the rack 18 to the pinion 19, and result in rotational movements of the shaft 20 in alternating directions. The rotational movements of the shaft and ratchet-wheel 27 in one direction are communicated through the pawls 34 to the wheel 28, resulting in intermittent rotational movement of said wheel in the direction indicated in Fig. 2. During said rotation of the wheel 28 the arm 40 is alternately lifted and dropped, by the engagement of the teeth 29 with the lug 41 and the passing 70 of said teeth from beneath the lug. The contact-piece 42 is thus alternately lifted into engagement with the springs 44 to electrically connect the same, and then drops out of contact therewith to again open the 75 circuit made therethrough. As the diameters of the ratchet-wheel and the wheel 28 are quite large proportionally to that of the pinion 19, it will be seen that a very slight movement of the rail, relatively to the ties 80 and the instrument housing supported thereon, will be sufficient to actuate the notched wheel 28 and cause one or more movements of the pivoted arm 40, with a resulting closing and opening of the circuit in which 85 is connected the switch device comprising the springs 44 and contact-piece 42. It will also be seen that the operation of the instrument is not dependent upon the maintenance of a precise relation of the instrument and 90 the normal position of the rail, or upon a definite range of movement of the rail relatively to the ties, or upon particular limits to such relative movement, for the reason that the permissible range of movement of 95 the plunger 13 each way from the average or normal position thereof is much greater than any probable variation in the relation of the housing and the rail. The instrument is especially desirable for use on a track 100 over which trains pass at high speed. Under such conditions the movement of the rail is very rapid, and with instruments in which the actuated parts have definite limits of movement, rapid operation thereof 105 results in pounding and excessive wear and stress upon the mechanism, so that the durability of such an instrument is thereby 110 greatly impaired. With my instrument, however, rapid operation of the rail-engaging 115 plunger results in reciprocating or alternating movement of only the relatively light and easily moved pinion, shaft and ratchet-wheel; while the cumulative effect of the several impulses upon the wheel 28 merely 120 causes the same to spin or revolve rapidly in a uniform direction. Overspeeding of the switch-arm 40 is impossible because the same 125 is actuated only by gravity during its downward movements. By the provision of the 130

spring-pressed arm 36, it is insured that when actuation of the wheel 28 ceases said wheel will assume a position at which the contact or switch-arm is in the lowered position thereof. The operating mechanism is so inclosed and protected by the housing that water or dirt cannot enter the same, and, as any probable variation in the normal relation of the rail and housing will not affect 10 the operation of the instrument, it will be seen that the operativeness thereof cannot be impaired by rain, snow, ice or other conditions of weather or seasonal changes.

Now, having described my invention, what 15 I claim and desire to secure by Letters Patent is:—

1. A railway track-instrument comprising, in combination with a track-rail, a housing supported beneath the rail, a rail-engaging member slidably held in the housing, yielding means pressing said member against the rail, a shaft journaled in the housing, a pinion and rack connecting said shaft with the rail-engaging member, and electrical circuit-controlling devices actuated by rotational movement of said shaft.

2. A railway track-instrument comprising,

ing, in combination with a track-rail, a housing supported beneath the rail, a rail-engaging member slidably held in the housing, yielding means pressing said member against the rail, a shaft journaled in the housing and geared to the rail-engaging member, a wheel revolvably mounted on said shaft, means for communicating to said wheel the movements of said shaft in one direction, and an electrical circuit-closing device actuated by said wheel.

3. A railway track-instrument comprising a housing, a reciprocable rail-engaging member slidable in said housing and adapted for movements of considerable extent relatively thereto, yielding means for pressing said member toward a track-rail, a rocking shaft actuatable by said rail-engaging member, a wheel ratchet-connected with said shaft and actuatable by rotation thereof in one direction, a yieldable detent for stopping said wheel in fixed normal positions, and a switch-member actuatable by movement of said wheel from said normal positions.

GEORGE H. CARLSON.
